APPARATUS FOR COATING METALLIC ARTICLES

Original Filed Nov. 7, 1927 2 Sheets-Sheet 2

UNITED STATES PATENT OFFICE

WILLIAM H. SOMMER, OF PEORIA, ILLINOIS

APPARATUS FOR COATING METALLIC ARTICLES

Original application filed November 7, 1927, Serial No. 231,621. Divided and this application filed June 26, 1928. Serial No. 288,485.

This invention has reference to an apparatus for coating metallic articles with "spelter," and its adaptation, as herein shown, is for iron or steel wire, but experience may show it to have other and various uses.

The method of coating a metallic article, such as wire, by which the invention is preferably practiced, consists in thoroughly cleaning the wire with acid and then drying the wire before it enters the "spelter" bath, and passing such wire thru a flux of preferably zinc ammonium chloride at the entrance and exit ends of such bath, and passing the coated wire immediately on its leaving the flux, at the exit end of the bath, thru a skimmer. The latter adapted to align itself to the axial movement of the wire and thereby prevent surface irregularities in the coating.

The apparatus, when used for wire, includes a plurality of skimmer members having supports which will permit the coated wires to be drawn from the "spelter" bath; perpendicular to the surface of the bath, or inclined thereto; and each of said skimmer members have preferably a "hair-pin" shape and are carried by their supports, in a manner to permit them to be easily and quickly removed and replaced, and also permit them to align themselves to the axial movement of the wires, whereby to prevent surface irregularities in the coating.

I prefer to use a shallow thickness or a thin layer of the zinc ammonium chloride and to position the skimmers in close proximity or next adjacent thereto, and thru these combined elements I not only prevent oxidation of the "spelter," by the prevention of the formation of sleeves on the wires, but their use enables me to use and materially increase the speed of 22" blocks, to speeds ranging from 15 to 30 revolutions per minute; whereas, without the use of such element or elements the rate of speed of such blocks would be from 5 to 7 revolutions per minute. Experience has also shown that

where high speeds have been attempted and the usual careful wiping employed, that the resulting coated wire is rough, caused by the "spelter" forming surface irregularities on the wire. These are eliminated by the use of my apparatus.

That the invention may be more fully understood, reference is had to the accompanying drawings forming part of this description, illustrating a preferred embodiment of the invention, in which:

Fig. 1 is a diagrammatic view of an apparatus by means of which the within described process may be practiced;

Fig. 2 is a longitudinal sectional view, broken away, showing a "spelter" bath with associated clean flux surfaces of zinc ammonium chloride and the skimmer positioned to direct the coated wire from the bath perpendicular to the surface of the bath;

Fig. 3 is a view similar to Fig. 2, except that the skimmer is shown directing the coated wire away from the bath at an inclination to the surface of the bath, and

Fig. 4 is an enlarged plan view of one of the skimmers, the same being shown in full lines in a position in relation to its support, as it would appear in Fig. 2, and in dotted lines in relation to its support, as it would appear in Fig. 3.

Like characters of reference denote corresponding parts thruout the figures.

Referring to Fig. 1, an apparatus for coating wire with "spelter" is shown, including an "annealing furnace" 1 to which the wires A to be coated, are directed from suitable reels, not shown, or from other suitable source. From the furnace 1 the wires are directed thru a "cleaning bath" 2 of acid suitable for the purpose, the length of which I prefer shall be longer than ordinarily used. From the bath 2 the wires are directed over a "drier" 3, for drying the cleansed wires, before they are caused to enter a suitable pan

4, containing the "spelter" bath 5 used as a coating for the wires A.

A compartment 6 is provided at the entrance end of the pan 4 and in this compartment and floating on the surface of the "spelter" is a liquid flux 7 of preferably zinc ammonium chloride. The wires A enter the bath thru this clean surface of flux and pass into and thru the "spelter," beneath a guide 8. The pan 4 may be of any desired length, and at its exit end there is provided a compartment 9 and in this compartment and floating on the surface of the "spelter" is a liquid flux 10 of zinc ammonium chloride similar to the flux 7. I prefer that this flux shall comprise a comparatively shallow body of such zinc ammonium chloride. The wires which have been coated with the "spelter" are directed upwardly thru the flux, by a guide 11.

I contemplate that the pan 4 will be wide enough to accommodate the coating of a multiplicity of wires, in suitable spaced relation, as is customary in the ordinary practice of galvanizing.

The coated wires leave the bath, preferably perpendicular to the surface thereof, as seen in Figs. 1 and 2, or may leave the bath at an inclination to its surface, as seen in Fig. 3. In each instance, a coated wire is fed or drawn thru a skimmer member 12, of which there is a plurality, one for each wire and said skimmer members are carried by a skimmer support, comprising pairs of overlying spaced bars 13 and 13' suitably supported at their opposite ends by the pan 4. In Figs. 1 and 2 the pairs of bars 13 and 13' are supported horizontally in spaced relation, in which position the skimmers 12 also assume a horizontal position with the coated wires moving vertically of the guiding means thereof. In Fig. 3 the pairs of bars 13 and 13' are arranged at an inclination to each other and the surface of the bath and in this position the skimmers are inclined to the vertical so that the coated wires guided thereby are directed away from the bath at an inclination to the surface of the bath.

The skimmer members 12 are duplicates of each other, so that the description of one will suffice for all. As shown, the member has preferably the form of a U bar or substantially hair-pin formation. It is best constructed from an elongated piece of wire bent backward at 14 to provide overlapping spaced portions 15 having their ends flattened, as at 16, and such flattened ends have meeting faces 17 formed or provided with complimentary or coinciding notches 18, which together provide a wire opening or guide for the passage of a coated wire there thru and the meeting faces 17 diverge outwardly, as at 19 to provide a throat for the said skimmer. In supporting the skim-

mers they lie transversely of and between the pairs of bars 13 and 13', either with their openings or guides disposed between said sets of bars 13 and 13', as shown in Fig. 2, and in full and dotted lines in Fig. 4, or forward of the set of bars 13', as shown in Fig. 3, and in dotted lines in Fig. 4. The skimmers are disposed in spaced relation on the bars 13 and 13' and lie between said sets of bars with the turned back portions 14 projecting from without the set of bars 13 to provide finger-holds to enable an operator to grip the same for inserting the said skimmers between the sets of bars 13 and 13' and to withdraw the same therefrom. Also spacing pins 20 are inserted thru the set of bars 13 to retain the rear end or finger-hold portions 14 of the skimmers in proper position and in working relation to each other, while at the same time the forward wire guiding portions of said skimmers can move sidewise or laterally that they may accommodate themselves to the axial movement of the wires, preventing irregularities in the surface of the coating which might arise from a scraping action on the skimmers, and also preventing unequal wear of the notches 18 forming the guides in the skimmers.

The skimmers being made from wire are light and therefore may be easily inserted or retracted and having the throat portions 19 permits them to be removed and replaced whether coated wires are threaded therethru or not. The throated and guiding ends being sufficiently resilient to be sprung apart.

The coated wires on leaving the bath may or may not pass over a suitable cooling means 21, see Fig. 1.

In using the term "spelter" I have reference to zinc or a zinc alloy.

This application is a division of the application for Letters Patent of the United States, filed by me November 7, 1927, Serial No. 231,621, entitled Method and apparatus for coating metallic articles.

What I claim is:—

1. In an apparatus for coating iron or steel wire with "spelter," in combination, a receptacle to hold the spelter and thru which the wire is adapted to be moved, a skimmer member thru which the coated wire passes having free moving ends, whereby its wire skimming portion may align itself to the axial movement of the wire and guiding means for the skimmer member disposed on opposite sides of said member.

2. In combination, a skimmer member comprising an element substantially U shaped and having its end portions flattened and provided with coating grooves forming a wire guide, and means to support said skimmer member whereby to permit its placement and removal from said support.

and to permit its skimming end to align itself to the axial movement of a wire.

3. In an apparatus for coating iron or steel wire with spelter, in combination, a receptacle to hold the spelter and thru which the wires are adapted to be moved, skimmer supports comprising spaced members, skimmer members thru which coated wires pass, said skimmer members lying freely between said skimmer supports, whereby the skimming portions of said skimmer members may align themselves to the axial movement of the wires, and spacing means on the said supports for the adjacent skimmer members.
